PRODUCTS FROM CATALYTIC CRACKING

Walter J. Schmidt, Jr., and Forrest H. Blanding,
Cranford, N. J., assignors to Standard Oil De-
velopment Company, a corporation of Delaware

Application December 29, 1949, Serial No. 135,654

4 Claims. (Cl. 196—52)

1

This invention relates to the catalytic conversion of hydrocarbon oils and pertains more particularly to a method of increasing the yield of heating or domestic furnace oil.

Economical oil refining processes dictate that a proper balance be maintained between the production of gasoline on the one hand and domestic furnace oil on the other. Both of these products are obtained from the same general refining operations, such as by crude distillation and cracking. In the past, the relatively large demand for gasoline, as compared with domestic heating oil, has made it possible to maintain the proper balance without difficulty since any excess production of furnace oil could readily be converted into gasoline by conventional cracking treatment.

In recent years, however, the demand for furnace oil has increased at a greater pace than the demand for gasoline so that at times there is a shortage of furnace oil produced when the cracking operations are geared to meet gasoline requirements. It is, therefore, important to be able to increase the ratio of furnace oil to gasoline produced during the cracking process.

The present invention provides a simple and effective method of increasing the proportion of furnace oil relative to the amount of gasoline formed during the cracking process.

It has been found that in the catalytic cracking process, the yield of heating oil is increased appreciably without loss of gasoline yield by cracking the oil under relatively mild conditions, separating the cycle gas oil into a heating oil fraction and a heavy gas oil fraction, removing the aromatics from the heavy gas oil fraction by a suitable solvent extraction and returning the paraffinic raffinate from the extraction step to the cracking operation.

When carrying out ordinary recycle operations wherein heavy cycle gas oil produced in the process is returned to cracking without solvent extraction, the gasoline yield and heating oil yield are generally increased as the conversion per pass is reduced. Even when withdrawing a fixed amount of heavy cycle gas oil as product, operation at low conversion with recycling will produce a considerably higher yield of gasoline and a slightly higher yield of heating oil than will once-through operation at high conversion. Since the increase in gasoline yield by recycling is much greater than the increase in heating oil yield, ordinary recycle operation is not an effective way of increasing heating oil production relative to gasoline production.

2

By extraction of the heavy cycle gas oil to remove the aromatics and utilizing the aromatic extract as fuel oil, returning the paraffinic raffinate to the cracking operation, the yield of gasoline from a given amount of feed stock will be higher than in a once-through single pass cracking operation without recycling but the gasoline yield will not be substantially affected as the conversion per pass or severity of cracking is reduced. On the other hand, the yield of heating oil from a given amount of feed will be appreciably higher than in the case of a once-through single pass cracking operation and the amount of heating oil will be increased as the conversion per pass is reduced. This is illustrated in the following table, wherein a heavy West Texas gas oil was catalytically cracked employing the fluid type cracking process at a temperature of 975° F. and a conventional type synthetic silica-alumina gel catalyst.

Operation	O. T.	Recycle of Heavy CGO		Recycle of Raffinate	
		1	1.12	1.33	1.12
Recycle Ratio.....	1	1.12	1.33	1.12	1.33
Vol. Percent Gasoline.....	43.4	44.0	45.5	45.6	45.3
Vol. Percent Heating Oil.....	19.6	19.2	19.8	22.6	25.5
Vol. Percent Hvy. CGO or Extract.....	20.4	19.0	21.2	19.0	21.2

The first column in the above table gives the volume of gasoline and heating oil produced in a once-through single pass cracking operation with no recycling of heavy gas oil. Columns 2 and 3 give the results produced when recycling different amounts of heavy gas oil without solvent extraction. In column 2 the amount of recycle oil as indicated by the recycle ratio is 1 part of fresh feed to .12 part of recycle gas oil; and in column 3 the recycle ratio gas oil is 1 part of fresh feed to .33 part of heavy cycle gas oil. Columns 4 and 5 show the relative volumes of gasoline and heating oil produced in accordance with the present invention in which the heavy cycle gas oil is extracted to remove the aromatics and the raffinate is recycle. Comparing columns 4 and 2 it will be noted that the amounts of material recycle (raffinate or heavy cycle gas oil) are the same and also that the amount of heavy oil withdrawn (extract or heavy cycle gas oil) are the same. Similarly, columns 5 and 3 are based upon equal recycle and withdrawal. In all of the operations illustrated in the table, the gasoline yield is substantially the same. However, by recycling the raffinate as

shown in columns 4 and 5, the amount of heating oil is materially increased without sacrificing the yield of gasoline. For example, by using the present invention and by recycling raffinate in the amounts shown in column 5, it is possible to increase the amount of heating oil by about 6% as compared to that which can be produced either in a once-through cracking operation or in a recycling operation wherein a portion of the total heavy gas oil is recycle.

For a better understanding of the invention, reference is made to the accompanying drawing which is a diagrammatic illustration of apparatus capable of carrying the invention into effect. The drawing illustrates a fluid type process for cracking of the oil, although it will be understood that other types of catalytic cracking operation may be used, if desired.

Referring to the drawing, the fresh feed to be cracked is introduced into the system through line 10. This fresh feed may be any suitable oil which is desired to crack into lower boiling fractions such as gasoline and heating oil. The oil passing through line 10 intermixes with a stream of finely divided cracked catalyst such as synthetic silica-alumina gel catalyst discharging through standpipe 11 at a controlled rate through valve 12. The catalyst introduced into the oil is at substantially regeneration temperature, such as a temperature of from 1050-1150° F. and the oil, prior to contacting with the catalyst, may be preheated to such temperature that the resulting mixture forms a suspension of oil vapors and catalyst at a suitable cracking temperature such as from 850° to 1000° F.

The resulting suspension is transferred through the transfer line 13 which terminates in an inverted cone distributor 14 located within the reactor 15. The cone distributor 14 is provided with a perforated grid at its upper end for dispersing the suspension over a substantial horizontal portion of the reactor. Upon entering the reactor, the velocity of the oil vapors is reduced to such point that the catalyst is allowed to settle into a relatively dense phase in the bottom portion thereof, which is maintained in a highly turbulent state by the vapors passing upwardly therethrough.

The oil vapors, after contacting with the catalyst at cracking temperature for a sufficient period to obtain the desired conversion, are removed from the top of the reactor through line 16 after passing through a suitable cyclone or other separating device 17 for removing entrained catalyst particles from the gas. The catalyst separated in the separator 17 is returned to the dense turbulent bed of catalyst in the reactor. The cracked vapors continue through line 16 and enter the bottom of a conventional fractionating tower 18 wherein they are subjected to fractional condensation.

The initial condensate formed in the bottom section 19 of the tower 18 may contain a small amount of catalyst carried over from the reactor. The condensate containing the catalyst is withdrawn from the bottom of the fractionator 18 through line 20 and may be recycled by means of pump 21 for further cracking treatment along with the fresh feed.

The tower 18 is provided with a lower trap-out tray 22 for collecting heavy cycle gas oil boiling above the boiling point of domestic heating oil, such as boiling above 600-650° F. To this end, the temperature in the intermediate section of the fractionating tower 18 is controlled to con-

dense constituents boiling above the furnace oil boiling range.

A second trap-out tray 23 is positioned in the upper portion of the fractionating tower 18 and is adapted to collect a furnace oil fraction which forms one of the final products of the process. The furnace oil fraction is withdrawn from trap-out tray 23 through line 24 and may be subjected to further stabilization, or distillation, or any further treatment required to produce a marketable product. Vapors remaining uncondensed after passing through the fractionating tower 18 are removed overhead through line 25 which leads to a condenser 26 wherein the gasoline fraction is liquefied. The products from the condenser 26 pass to a receiver 27 wherein the liquid condensate is allowed to separate from uncondensed gases and vapors. The uncondensed vapors and gas are removed from the receiver 27 through line 28 and may be passed to any suitable equipment for recovery of the desired components therefrom. The gasoline formed in the process is withdrawn through line 29 and may be stabilized or subjected to any further treatment desired.

Returning to the fractionating tower 18, the heavy gas oil collected in the lower trap-out tray 22 is withdrawn through line 30 and subjected to solvent extraction to separate the paraffinic constituents from the aromatic constituents. To this end, the fraction may be passed to a solvent extractor 31 into which is charged a suitable solvent through line 32. This solvent may comprise any suitable material capable of selectively extracting aromatic constituents from the paraffinic constituents. Such solvents may include, for example, such materials as liquid sulfur dioxide, phenol, dichlorodimethyl ether, furfural, chlorinated hydrocarbons such as carbon tetrachloride and the like.

Any suitable means may be used for effecting intimate contact between the heavy cycle gas oil and the solvent. As illustrated, the solvent is introduced near the top of the extractor and passes downwardly in countercurrent contact to the oil. The solvent containing the aromatics is withdrawn from the bottom of the extractor through line 33 and may be passed to a distilling column 34 wherein the extract is heated to vaporize the solvent. The extract is withdrawn from the distilling zone 34 through line 35 and the vaporized solvent is drawn overhead through line 36 which leads to a cooler 37, which serves to liquefy the solvent prior to the return to the extractor through line 32. The extracted raffinate is withdrawn from the top of the solvent extractor through line 38 which leads to a distilling column 39 wherein the raffinate may be heated to vaporize the solvent absorbed therein. In such case, the vaporized solvent is removed from the distilling column 39 through line 40 and is combined with the vaporized solvent from the distilling column 34 passing to the cooler 37. Following the removal of the solvent from the raffinate, the latter is passed through line 41 and pump 42 and combined with fresh feed passing to the cracking zone. It is not necessary, in all cases, to subject the raffinate to distilling treatment to remove solvent therefrom. In such cases, the raffinate from the extractor 31 may be recycled without being subjected to distilling for removal of solvent vapor.

In some cases, the initial condensate formed in the bottom of the fractionating tower 18 may be passed to the solvent extractor 31 through line

43, particularly where the initial condensate is relatively free of catalyst particles carried overhead from the reaction zone.

Returning to the reactor 15, a stream of catalyst containing carbonaceous deposits formed during the cracking reaction is continuously withdrawn from the reactor 15 through standpipe 44, which may be provided with suitable aerating lines to maintain the catalyst in a fluid condition. Prior to removal of the catalyst from the reactor 15, it may be subjected to a stripping operation by injection of steam through line 45 to remove vaporizable hydrocarbons therefrom. The stripped hydrocarbons discharge from the base of the standpipe 44 into a stream of air passing through line 46, which carries the catalyst into the regenerator 47. Within the regenerator the catalyst is subjected to oxidation to burn carbonaceous deposits. The regenerated catalyst is withdrawn from the regenerator 47 through the standpipe and intermixed with fresh feed as previously described.

The present invention comprehends a process wherein the initial feed is subjected to catalytic cracking under relatively mild conditions and the heavy cycle gas oil produced in the process is solvent extracted to remove the aromatics and the non-aromatic fraction is recycled back to the cracking zone. The extent of cracking within the reactor 15 may be controlled by regulating the amount of catalyst introduced into the oil charge, by regulating the level of the dense phase of catalyst in the reactor 15, by the feed rate of oil through the reactor and the temperature maintained within the reactor. As previously stated, cracking conditions should be relatively mild so that the extent of conversion of the fresh feed as measured by gas oil disappearance during its initial passage through the cracking zone should be in the range of from 30 to 40%, preferably about 35%.

Having given a detailed description of the invention, it will be understood that it embraces such other variations and modifications as come within the scope of the following claims.

We claim:

1. A process for the conversion of heavy hydrocarbon oils into lower boiling furnace oil and gasoline, which comprises cracking fresh un-cracked oil in the presence of a catalyst under conditions controlled to convert from about 30 to 40% of said fresh oil into gasoline constituents, fractionating the resulting products to segregate a gasoline fraction, a light furnace oil

fraction and a heavy cycle oil fraction, removing said light furnace oil fraction as a product of the process, treating said heavy cycle oil fraction to remove aromatics therefrom and subjecting said extracted oil to further cracking treatment with said first-named oil.

2. In a process for catalytically cracking heavy hydrocarbon oils to form lower boiling furnace oil boiling between about 450 and 650° F. and to form gasoline, the method of increasing the amount of furnace oil relative to the amount of gasoline formed during said cracking process, which comprises passing the fresh oil to be cracked through a cracking zone maintained at cracking temperature, contacting said oil within said cracking zone with an active cracking catalyst for a period sufficient to convert between 30 and 40% of said oil into gasoline, thereafter fractionating the resulting products to segregate a gasoline fraction, a light furnace oil fraction and a heavier cycle oil fraction, removing said light furnace oil fraction as a product of the process, treating said heavy cycle oil fraction with a solvent capable of selectively extracting aromatic constituents therefrom, separating the solvent containing said aromatic constituents from the remainder of said oil and thereafter returning oil so extracted to the cracking zone for further cracking treatment in the presence of said first-named oil.

3. The process defined in claim 2 wherein the oil is cracked in the presence of a synthetic silica-alumina gel catalyst.

4. Process defined in claim 3 wherein cracking is carried out in the presence of finely divided catalyst.
